UNITED STATES PATENT OFFICE.

ALEXANDRE COUTURE, OF BALTIMORE, MARYLAND.

RAIL-JOINT.

1,234,632.

Specification of Letters Patent. Patented July 24, 1917.

Application filed March 10, 1917. Serial No. 153,819.

To all whom it may concern:

Be it known that I, ALEXANDRE COUTURE, a citizen of France, and a resident of Baltimore, in the county of Baltimore and State 5 of Maryland, have invented certain new and useful Improvements in Rail-Joints, of which the following is a specification.

My invention relates to a device for holding rails and refers particularly to a device 10 whereby the rails are held by means of wedges between the rails and a supporting shell.

By employment of my device the use of bolts and nuts is entirely eliminated and the 15 rails are held absolutely free from lateral and vertical movement, while allowing sufficient horizontal movement caused by changes of temperature. It is economical in production, strong in construction and 20 certain in operation. It allows of the change of rails with a minimum expenditure of time and labor and is readily applied to all shapes of rails.

Modified forms of my device are illustrated in the accompanying drawings in which similar parts are designated by similar numerals.

Figure 1 is a perspective view of one form 30 of a device of my invention, partly broken away.

Fig. 2 is an end view of Fig. 1 with parts assembled.

Fig. 3 is a top plan view of Fig. 1 with parts assembled.

Fig. 4 is an end view of a modified form 35 of a device of my invention.

Fig. 5 is a side elevation of Fig. 7.

Fig. 6 is a perspective view of a modified form of the supporting shell.

Fig. 7 is an end view of the supporting shell, of Fig. 6, with rail and wedges assembled.

Fig. 8 is a perspective view of one of the 45 wedges of Fig. 7.

Fig. 9 is a perspective view of the other wedge of Fig. 7.

In the form of my device illustrated in Figs. 1, 2 and 3, the rail supporting shell 10 comprises the two similar side members 11, 11, parallel to the rail web 25, and the bottom plate 12, of such a size and shape that the foot 13 of the rail will rest upon the bottom plate 12 and the head 14 of the rail will extend upwardly from between the 50 side members 11, 11. The bottom plate 12 has the cut-outs 15, 15, 15, 15 for the inser-

tion of spikes 16, 16, to bind and hold the bottom plate 12 and the rail foot 13 to the cross-ties 17, 17. The bottom plate 12 also has the cut-outs 18, 18 for the insertion of 60 spikes 19, 19 to hold the bottom plate 12 to the cross-tie 20. Upon the interior face of the bottom plate 12 and extending upwardly are the lugs 21, 21, 21, 21. These lugs 21, 21, 21, 21 extend through the openings 22, 22, 22, 22 of the rail foot 13, the openings 22, 22, 22, 22 being somewhat larger than the lugs 21, 21, 21, 21 to allow of slight horizontal movement of the rail on account 70 of expansion or contraction due to variations of temperature.

Upon each side of the rail and slidably removable between the rail and the supporting shell 10 are two wedge shaped binding members 23 and 24. The binding member 23 bears upon the lower surface of the rail head 14, the surface of the rail web 25, a portion of the rail foot 13 adjacent to the rail web 25, and the upper inner portion of the side member 11 of the supporting shell 10, and extends over the top of the side member 11 of the supporting shell 10. The binding member 24 is slidable within the space formed by the binding member 23, the upper surface of rail foot 80 13 and the interior surface of the side member 11 of the supporting shell 10. The wedges 23, 23 have conduits 26, 26 for electric wires if desired.

The operation of the device is as follows: 90 The ends of the two rails are introduced into the supporting shell 10 from opposite directions, and the lugs 21, 21 placed within the openings 22, 22 of the rail foot 13. The two binding members 23, 23 are then introduced between the rail and the supporting shell 10 from opposite ends, the large end of each binding member 23, 23 being first introduced. When the binding members 23, 23 are thus situated, the two binding members 24, 24 are introduced from opposite ends, small ends first. The members 23, 23 and 24, 24 are then driven home in order to make a firm binding connection between the rail and the rail supporting shell 10. The 95 binding members 23, 24, which may be somewhat longer than the side member 11 of the shell 10, are flared by means of blows to prevent their accidental disengagement or withdrawal. The spikes 16, 16, 16, 16 are 100 then driven into the ties 17, 17 sufficiently to firmly engage the rail foot 13 and the

bottom shell member 12, but allowing the longitudinal movement of the rail due to change of temperature. The spikes 19, 19 are then driven into the tie 20 sufficiently 5 to firmly hold the supporting shell 10 to said tie.

In the modification shown in Fig. 4, the 10 upper edges of the side members 11, 11 are inclined from end to end, in opposite directions to each other with respect to the base 12, and the edges of the binding members 34, 34 abuttable thereon, are similarly inclined. The upper edges of the side members are parallel to the rail web 25.

15 In the modification shown in Figs. 5, 6, 7, 8 and 9, rail supporting shell 27 is comprised of the side member 11, the base member 12, and the side member 36. The side member 36 is composed of the upwardly and 20 inwardly inclined member 28 and the downwardly inclined member 29, the upper portion 30 of the side member being abuttable upon the under side of the rail head 14, and the inclined member 29 being abuttable 25 upon the side of the rail web 25. Integral with the inclined member 29 are studs 31, 31, these studs being capable of insertion within the holes 32, 32, of the rail, and may be arranged to coincide with the holes ordinarily found in rails, intended for bolting 30 to the ordinary fish plate. The upper edge 33 of the side member 11 is inclined with respect to the plane of the base 12 but is parallel to the rail web 25. The two wedge-shaped binding members 34 and 35 are 35 capable of slidable introduction into the uniform space between the rail and the side member 11 and of binding contact therewith and with each other. The operation of this

modification is as follows: The ends of the 40 two rails are inserted into the supporting shell 27 from opposite ends, the space between the inner surfaces of the lugs 31, 31 and the side member 11 being sufficiently great to allow of the passage of the rail 45 web 25 past the lugs; the rail is then moved sideways to allow the lugs 31, 31 to enter the holes 32, 32 and the rail abutted against the member 29, the binding member 34 is then inserted and the binding member 35 is 50 thus inserted and driven home, the device thus holding the two rails in firm position.

I do not limit myself to the size, number, arrangement of parts as shown and described, all of which may be varied without 55 going beyond the scope of my invention as described and claimed.

What is claimed, is:

A rail joint comprising in combination, a rail supporting base, the sides of which extend upwardly and inwardly, and are parallel to the webs of rails resting upon the base and inclined to the plane of the base, said sides being spaced from the heads of the rails, a plurality of wedge-shaped members 60 capable of longitudinal movement between the rails and the side members, said wedge-shaped members binding upon the upper edge of the side member, upon each other and upon the heads, webs and feet of the 65 rails preventing vertical and transverse movement of the rails and means for allowing a limited longitudinal movement of the rails upon the base.

Signed at New York city in the county of 75 New York State of New York this 5 day of March 1917.

ALEXANDRE COUTURE.
